UNITED STATES PATENT OFFICE

123,316

DESIGN FOR A CABINET FOR PHONO- GRAPHS OR THE LIKE

Clifford Brooks Stevens, Milwaukee, Wis., assignor to The John Gabel Manufacturing Company,
Chicago, Ill., a corporation of Illinois

Application March 11, 1940, Serial No. 90,824

Term of patent 3½ years

To all whom it may concern:

Be it known that I, Clifford Brooks Stevens, a citizen of the United States, residing at Milwaukee, in the county of Milwaukee and State of Wisconsin, have invented a new, original, and ornamental Design for a Cabinet for Phonographs or the like, of which the following is a specification, reference being had to the accompanying drawing, forming part thereof.

Fig. 1 of the drawing is a perspective view of a cabinet for phonographs or the like, showing my new design; and

Fig. 2 is an elevational view of the right-hand side thereof.

I claim:

The ornamental design for a cabinet for phonographs or the like, substantially as shown.

CLIFFORD BROOKS STEVENS.
